UNITED STATES PATENT OFFICE

FREDERICK KOHNLE, OF DAYTON, OHIO, ASSIGNOR TO THE MONARCH MARKING SYSTEM COMPANY, OF DAYTON, OHIO, A CORPORATION OF OHIO

TYPE CHASE

Application filed July 14, 1930. Serial No. 467,838.

This invention relates to improvements in type chase or holder for use in a machine of a character of price tag marking machines in which the user makes or changes the type printing set-up as the price or marking data to be printed upon price tags. The chase is arranged to be readily slipped into or out of place in the machine and type bars each individually sustained in the holder so that a printing set-up can be conveniently and quickly made or changed by the operator of the machine.

The holder is preferably provided with several parallel slots for several rows or lines of type, with a wall of each slot provided with a series or plurality of parallel longitudinal grooves, each groove serving to guidingly receive longitudinal fins extending from the type bars individually locating and sustaining the type side by side or in spaced relation in a type receiving slot of the holder.

The present invention is primarily directed to the structure of the grooved wall 25 of the type receiving slots which wall may also constitute a division wall for several slots. Therefore, the object of the invention is to form a type bar sustaining wall of a holder of a sheet metal plate having its opposite ends morticed within the body of the holder facilitating the manufacture of the holder and providing a wall of greater stability and durability.

Further objects and advantages will be 35 more fully set forth in a description of the accompanying drawings, in which:

Figure 1 is a front elevation of the improved type holder shown removably mounted within a printing head of a tag marking machine with the head depressed, bringing the type for a printing impression upon a tag stationed upon a stationary platen beneath the printing edge.

Fig. 2 is a section on line 2—2, Fig. 1.

Fig. 3 is an enlarged section through the improved type holder on line 3—3, Fig. 2.

Fig. 4 is a perspective view of one of the type holding partition walls of the holder.

Fig. 5 is a top plan view of the holder 50 with the partition walls removed.

Fig. 6 is a perspective view of the holder with the partition walls removed.

The holder or chase, in the drawings, is shown within a swinging head of a price tag marking machine which serves to hold the type bars against vertical or longitudinal displacement in the holder and imparts the printing pressure directly to or upon the type bars which are sufficiently loose in the holder to relieve the holder of any printing impression impacts.

The upper ends of the type bars each, when making an impression, abuttingly bear against a plane under face of the printing head. The type bars are sustained in the holder by a shouldered engagement of a rib or fin extending longitudinally from one side of the type, and the end of a groove in a wall of the type receiving slot of the holder. The holder possesses the general characteristics of the holders now commercially used, in which the type bars are easily slipped out and into the holder for making or changing a printing set-up.

The type bars are selectively and definitely set into and projected into rectangular slots in the holder with a wall of each slot provided with a series of grooves extending from one end for a portion of the depth of the wall. The grooves are uniformly spaced, the spacing governed by the size of the type so as to adapt the type to be set side by side approximately in contact with each other.

The longitudinal rib or fin on one side of the bar adapts the bar to be guidingly engaged into a selected groove in the holder type receiving slots for making the printing set-up. This interlocking connection sustains the type bars against lateral displacement, and supports the bars within the holder. The type receiving slots are usually arranged in parallelism and as close together as possible to make a compact several line set-up capable of printing at least a four line set-up upon small sized tags, as for instance, jewelry tags

with a very small sized point of type.

The division walls for the slots, therefore, are required to be exceedingly thin. It is desirable to die cast the holder, which method, however, has not been very practical on

account of the extreme thinness of the grooved partition walls forming the type receiving slots, as the metal alloy used in die casting will not provide a partition wall of sufficient stability.

With the present invention the partition walls represent grooved steel plates morticed into the die casting or body of the holder.

Referring to the drawings, 1 indicates the forward end of a printing head of a type marking machine in which the type holder or chase 2 is removably mounted. The head is reciprocated or swung toward and from an impression platen 3, represented as an elastic pad recessed into the surface of the table of the machine over which the tags to be price marked are successively advanced or moved to bring the tags appropriately beneath the printing head. The lower side of the head is channeled to receive the holder, with the inside face of the side walls 4—4, which form the channel, each provided with longitudinal grooves or slide ways 5, respectively receiving the flanges 6—6 extending from the opposite sides of the body portion of the holder 2.

The type holder 2 constitutes a rectangular casing structure provided with a plurality of parallel type bar receiving slots there-through in which the partition walls forming the slots are steel plate inserts or partitions 7, each morticed into grooves formed in the body of the holder 2.

A flange 8 extends from the forward side of the body of the holder continuous with the flanges 6—6 of the side walls and terminates with a finger hold 9. The holder supporting flanges 6—6 which slide into the guide ways of the printing head are relatively of different lengths, one extending for the full length of the body of the holder while the other for only a slight portion thereof. This facilitates in making entry with the slide ways and allows the holder to be slightly tilted to clear the upper ends of the type bar, projecting through and beyond the upper face of the holder, from the base surface of the channel in the printing head with which the butt end of the type bars engage when making an impression.

The opposite front and rear walls of the casing have a plurality of aligned grooves 10 therein for the full height measurement of the walls, into which the steel partition plates or inserts 7 are morticed, thereby providing a plurality of type receiving slots 11.

Each partition plate in one face side has a series of parallel grooves 12 milled therein extending from one edge longitudinally of the plate partially across the face thereof with the terminal of each groove providing a shoulder or stop for the fin or rib of a type bar when slidably engaged into the groove. The fin independently supports its type bar

within the holder without disturbing the type bar set next adjacent thereto, and also permits the type bars to be selectively spaced from one another within a slot. The spacing of the grooves 12 is preferably governed by the cross-sectional measurement of the type bars.

The partition plates are made of steel material of a very thin gauge and the grooves for the fins of the type bars accurately machined therein, before the plate is inserted in the body of the holder.

To securely hold the partition plates or wall inserts rigidly in position the opposite vertical edges of the plates are upset at several points as indicated at 14—14, the upsetting forming burrs or protuberances which bite into the metal of the holder when the plates are driven into the morticing grooves of the holder. The body of the holder being a die casting has the grooves for morticing the partition or insert plates cast therein. To allow the casting to be withdrawn from the mold or die it is necessary that the side walls of the grooves be slightly inclined or tapered to give the necessary draft. Likewise, at the one or lower end of the grooves, the walls flare slightly outwardly due to the filleting or rounding off of the corners of the mold or die.

The upper end of the groove, therefore, can be made extremely narrow to correspond to the small gage of the plate insert. By upsetting the opposite longitudinal edges of the plate at several points, preferably in the lower half of the plate, with the upsetting at the several points on each edge in relative varying degrees corresponding to the degree of taper or draft allowed for the grooves, the plates can be inserted into the grooves, under a drive fit in absolute perpendicular plane. As the wall surfaces of the plates or inserts are absolutely plane the type very snugly fit in the slots in the holder. This materially improves the structure of the holder and results in obtaining a higher quality printing without locking or clamping the type bars in place.

As it is only necessary to provide the type bar with one guide and sustaining fin on one side of the type bar, each type receiving slot in the holder has a smooth surfaced side wall and a grooved opposite side wall with the grooved wall for each slot representing a steel plate insert. It, therefore, follows that for one of the end slots of the series, a steel plate insert serves as a liner bearing directly against a wall of the holder.

Having described my invention, I claim:

1. A type chase, comprising, a casing having an opening therethrough, sheet metal plates morticed into opposite walls of said casing in definite spaced relation dividing the opening into a plurality of type receiving slots, the edges of the plates upset at

several points providing fins for binding the plates within the morticing in the walls of the casing.

2. A type chase, comprising, a casing having type receiving slots therethrough, each slot for holding several bars of type in assembled alignment side by side and each type bar interlockingly engaged with a wall of the slot, individually sustaining the bars within the casing, said casing at relatively opposite sides provided with flanges for slidably engaging within slide ways of a printing head, said flanges being of different length to adapt one flange to be engaged with its 15 guide way in advance of the other.

In witness whereof, I hereunto subscribe my name.

FREDERICK KOHNLE.
